DESIGN FOR A SHOE

Dominick La Valle, Marlboro, N. Y.

Application October 17, 1934, Serial No. 53,655

Term of patent 3½ years

To all whom it may concern:

Be it known that I, DOMINICK LA VALLE, a citizen of the United States, residing in Marlboro, in the county of Ulster and State of New York, whose post office address is 632 Broadway, New York, N. Y., have invented a new, original, and ornamental Design for a Shoe, of which the following is a specification, reference being had to the accompanying drawing, forming part thereof.

Fig. 1 is a plan view of a shoe, showing my new design.

Fig. 2 is a rear elevation of the shoe, slightly in perspective.

I claim:

The ornamental design for a shoe, as shown.
DOMINICK LA VALLE.
